STOKER CONTROLLING SYSTEM

William W. Hallinan, Mendota, Ill.

Application December 1, 1939, Serial No. 307,056

20 Claims. (Cl. 236—10)

The present invention relates to stoker controlling systems, and is particularly concerned with stoker systems including controlling devices which are adaptable for use in all kinds of coal stoker furnaces and heating systems, whether they be hot air, hot water, steam, or vapor.

One of the objects of the invention is the provision of an improved coal stoker system which is adapted to provide for the anticipation of the amount of heat needed, responsive to any room demand, and to provide a sufficient amount of heat, without the over-run of temperature which occurs with the coal stoker systems of the prior art. In order to point out particularly the advantages of the present invention, a comparison with the structures and disadvantages of the prior art coal stoker systems is necessary, as follows.

In the standard coal stokers of the prior art the stoker feed is usually set at a given coal feed, such as, for example, fifty pounds per hour, and the air supply for combustion of the coal is manually adjusted for this predetermined feed of coal. The feed of coal by the stoker is turned on when the room thermostat closes an electric circuit and calls for heat, the electric circuit from the thermostat energizing the stoker feed motor through suitable relays.

The stoker operates in this predetermined manner with the feed of a predetermined amount of coal per hour, and the supply of air at a fixed rate, as long as the room thermostat calls for heat. When the temperature in the room has risen to such a value that the thermostatic switch in the room is opened, that is, when the thermostat is satisfied, the opening of the circuit at the thermostat de-energizes the motor through suitable relays and stops the stoker in the devices of the prior art. Then a large amount of burning coal is in the furnace, which continues to produce heat in greater quantity than can be used, and it is, of course, impossible to prevent this further production of heat by the coal bed in the furnace, and the room temperature is over-run ordinarily from ten to fifteen degrees in the devices of the prior art.

This means uneven temperature and discomfort in the home, and much coal is wasted not only in the over-run that is brought about by such devices of the prior art, but the coal is also wasted on account of the increased consumption of coal when a stoker is operated in this manner.

Furthermore, when the stokers of the prior art operated in this manner, with a manual adjustment of the air supply, and the stoker was shut

down, the supply of air was also shut down, and there was practically no air delivered to burn the coal which has just entered the furnace and was being ignited by the bed of coals. Therefore, in the devices of the prior art, the furnace smokes badly and covers the heating surfaces with soot. Of course, the covering of the heating surfaces with soot prevents the most efficient transfer of heat from the combustion gases to the walls of the furnace or to the water in the boiler, and the soot must be cleaned out, and the soot also represents waste, on account of the fact that it is the product of incomplete combustion.

The stokers of the prior art are also subject to the disadvantage, when they operate in this manner, of producing more and larger clinkers, as the fuel bed is always very deep, and with a deep fuel bed it is difficult, and practically impossible, to force the air for combustion through the fuel bed.

Such a deep fuel bed also produces spirals or trees of coke in the bed, which break up in large lumps, forming the large cracks in the fuel bed, through which all of the air flows, instead of being applied uniformly to the coal bed for uniform combustion.

In brief, the stokers of the prior art are not adapted to be properly adjusted to bring about complete and efficient combustion, and smoking occurs also because of the fact that the deep fuel bed, with cracks or holes in it, allows the air to escape through to the top of the fuel bed, without mixing with the carbon in the coal.

Of course, this type of operation of the devices of the prior art is also very wasteful of fuel, as the carbon dioxide will at times amount to eight percent, and then run to fifteen or twenty percent, and then on to smoke; and thereafter decrease again to eight percent, all in one run of the furnace.

As the devices of the prior art cause an over-run of the temperature, this is responsible for the user endeavoring to change the coal feed to try to make it hold the proper temperature. Naturally the user thinks he is feeding too much coal when the room temperature is over-run. When the user cuts down the coal feed, the stoker is then not able to handle the job of heating the rooms on a colder day. In order to get sufficient heat on a colder day, the user then increases the coal feed, and the result is that the stoker is never in proper adjustment.

It is my experience that from twenty-five to thirty-five percent more coal is used in the de-

vices of the prior art, and I have found that in a standard stoker, which had been installed for two and one-half years, the coal consumption was reduced approximately one-third by the installation of the system embodying the present invention, and the over-run of the room temperature was so reduced that it was imperceptible to me, even during the Spring and Summer, when it is most difficult with a coal stoker to regulate the heat required.

One of the objects of the present invention is the provision of an improved coal stoker system in which provision is made for adjustment of the amount of air supplied for combustion to that required for the furnace under different operating conditions.

Another object of the invention is the provision of an improved coal stoker system in which the foregoing disadvantages of the prior art devices, such as smoking, formation of soot, temperature over-run, wasteful consumption of coal, and other disadvantages are eliminated.

Another object is the provision of an improved coal stoker system in which the amount of heat required for a room demand is adapted to be anticipated by the controlling devices and the heat generated in the furnace so adjusted to the demand that there is practically no over-run of the room temperature beyond that at which the thermostat is set.

Another object of the invention is the provision of an improved heating system which is adapted to be operated with a relatively thin fire-bed by means of which the waste of coal is eliminated and better operation and combustion facilitated through the avoidance of a deep bed of coals, which have a tendency to form cracks and holes that pass the air supplied to the bed without the uniform air distribution which is necessary to efficient combustion.

Another object of the invention is the provision of an improved coal stoker system which is adapted to operate smoothly and uniformly and to maintain a substantially uniform room temperature with a more efficient consumption of coal and less heat losses than the devices of the prior art.

Other objects and advantages of the invention will be apparent from the following description and the accompanying drawings, in which similar characters of reference indicate similar parts throughout the several views.

Referring to the four sheets of drawings:

Fig. 1 is a diagrammatic side elevational view of a coal stoker system shown in connection with a hot air furnace embodying the invention, the furnace and certain other parts of the system being shown in vertical section;

Fig. 2 is a top plan view of the diagrammatic installation of Fig. 1, with the furnace housing in section;

Fig. 3 is a larger fragmentary view of the motor mounting and the air damper, by means of which an adequate supply of air is assured for the bed of coals, after the stoker feed has been turned off;

Fig. 4 is a fragmentary end elevational view of one end of the motor and driving mechanism, with the housing partially broken away, to show an electric heating element;

Fig. 5 is a fragmentary sectional view, taken through a thermostatically actuated variable diameter pulley, taken on the vertical plane of the line 5-5 of Fig. 4, looking in the direction of the arrows;

Fig. 6 is a fragmentary view, including a wiring diagram for the motor control;

Fig. 7 is a view similar to Fig. 1 of a modification in which the thermostat of the variable diameter pulley is subject to the action of heated air from the plenum chamber of the furnace;

Fig. 8 is another view similar to Fig. 1 of a modification in which a fixed thermostat is subjected to heat from the air in the plenum chamber, by means of a copper extension tube and a bulb located in the plenum chamber;

Fig. 9 is an axial sectional view, taken through a spring pressed variable diameter pulley, which may be utilized for the driven pulley in certain embodiments of the invention;

Fig. 10 is a fragmentary end elevational view of the spring pressure adjustment of the pulley of Fig. 9;

Fig. 11 is a fragmentary sectional view, showing another mode of location of the thermostatic bulb in heat conducting contact with the metal of the housing forming the plenum chamber.

Referring to Figs. 1 and 2, 20 indicates in its entirety a coal stoker system, shown in connection with a hot air furnace 21, having a furnace casing 22, forming a plenum chamber 23.

It should be understood that the present invention may be used with all kinds of furnaces employing coal stokers, such as hot water boilers, steam boilers, vapor systems, etc., in which case the thermostatic control may be connected to be actuated by the heat of the water, vapor, or steam in the boiler, instead of the air in the plenum chamber 23.

35 The furnace 21 is provided with a retort 24 of suitable construction for containing the fire-bed, and the furnace casing 22 is provided with the usual cold air inlets 25 and the hot air outlets 26 leading from the frusto-conical bonnet 27.

40 A furnace retort 24 communicates through a suitable coal feed tube 28 with a coal hopper 29, having cover 30, and the coal in hopper 29 descends by gravity into engagement with a suitable feed screw 31 in the coal feed tube 28. The 45 retort 24 is also in communication with an air supply tube 32, leading from a centrifugal blower 33, which is provided with a drive shaft 34, having a suitable centrifugal impeller in the housing 35.

50 The inlet of the centrifugal blower 33 may be at either or both ends 36, 37 of the housing, and the bearing for the shaft 34 at the end 36 of the housing is preferably located inside the housing so that the shaft does not protrude, and a centrally located inlet opening 38 may be provided with a closure 39 for controlling the supply of air to the blower 33.

The outlet 40 of the centrifugal blower 33 is, of course, connected with the air tube 32.

55 The stoker includes a suitable base 41, which carries the blower 33 and also carries a gear case 42, provided with a bearing for the blower shaft 34, and with suitable speed reduction gears for driving the coal feed screw 31.

60 The shaft 34 may extend through the gear case 42 and be provided with a thermostatically controlled variable diameter pulley 43 fixedly secured thereon for driving the shaft 34 by means of a wedge-shaped leather or rubber belt 44, which is driven by a V-shaped pulley 45 carried by the motor shaft 46.

65 The motor 47 may consist of a substantially constant speed motor of any standard construction, adapted to maintain a substantially constant speed for the loads for which it is con-

structed, and the motor 47 is preferably provided with a base 48, which may be secured upon a supporting plate 49.

The supporting plate 49 is provided with a pair of depending apertured lugs 50 adapted to receive a stub shaft 51, which is mounted in the bifurcated end lugs 52 of a motor-supporting bracket 53.

The bracket 53 may be fixedly secured to a frame member 54 carried by the base 41, and thus the motor 47 is pivotally supported on the base for the purpose of maintaining the belt 44 in a taut condition.

The motor pivot shaft 51 is preferably centrally located under the motor, or it may be located slightly to one side, to utilize the motor weight, to exert a pull on the belt 44. When the motor support has its pivot centrally located under the motor, the supporting plate 49 is preferably provided with a laterally projecting arm 55, which is secured by means of an eye screw to one end of a helical coil spring 56. The other end of the helical coil spring 56 may be threaded and provided with nuts for securing it to an angle bracket 57 carried by a frame member located on the base 41, such as, for example, the wall of the hopper 29.

The lower end of the spring 56 has a hook engaging the eye on the arm 55, providing a pivotal connection. The spring 56 may be provided by means of the adjustable nuts and adjustable eye screw, with a predetermined tension for urging the motor in a clockwise direction about the axis of the shaft 51 and maintaining a tension on the belt 44.

The stub shaft 51 is preferably fixedly secured to the apertured lugs 50 and rotatably mounted in the bracket 53 so that the shaft rotates with the motor 47. At one end the shaft 51 is provided with a crank arm 90, which is pivotally secured by a pin 91 to a connecting rod 92. The connecting rod 92 preferably has threaded adjustable ends, which are secured in a threaded bifurcated yoke 93, 94 at each end and fastened by a lock nut 95 so that the length of the connecting rod 92 may be adjusted.

The yoke 93 is pivotally secured to a damper lever 96 by a pin 97. Damper lever 96 is pivotally mounted on the lower housing 35 by a pin 98, and it preferably carries a damper disc 39. The damper or air valve 39 is adapted to slidably engage the air inlet 38 of the blower housing 35, and thus the tilting movement of the motor is adapted to control the movement of the damper 39 through the intermediary of the levers 90 and 96 and connecting rod 92.

The driven pulley 43 on the shaft 34 is preferably a thermostatically controlled variable diameter pulley of the type shown in Fig. 5. This pulley may be any one of a number of different constructions disclosed in my prior applications, Case 1 Patent No. 2,210,976, filed March 15, 1938, of which this is a continuation-in-part or Case 2, Serial No. 313,673, filed January 13, 1940, of which Fig. 5 is exemplary.

The variable diameter pulley 43 preferably includes a pair of relatively movable pulley sections 101, 102, each of which is provided with a radially extending flange 103, 104, having opposed frusto-conical belt-engaging surfaces 105, 106.

The pulley section 101 has an elongated cylindrical hub 107, which is fixedly secured to the shaft 34 by means of a set screw 108. The pulley section 102 has an elongated tubular hub 109, 75

having a cylindrical bore 110 for slidably engaging the hub 107.

The tubular hub 109 may be provided with a pair of axially extending slots 111 which are adapted to pass the legs of a U-shaped member 112 which are attached to the inner hub 107, forming a frame for the support of a bellows thermostat 113.

The legs of the U-shaped member 112 are fixedly secured to the hub 107 by screw bolts 114 passing through these legs and threaded into threaded bores in hub 107.

A stop member 115 may be mounted on the bolt 114 and clamped against each leg of the U-shaped member 112 for the purpose of limiting the movement of the sections 101, 102. Each stop member 115 has a slot 116 for bolt 114 and a pair of inwardly extending flanges 117 for engaging an end plate 118.

The rotation of the pulley section 102 with respect to pulley section 101 is limited by inter-engagement between the walls of the slot 111 and the U-shaped member 112, but sliding movement between these sections is permitted and is controlled by means of the thermostat 113.

The thermostat 113 preferably comprises a corrugated metallic bellows, having both ends closed, and the bellows is filled with a thermally expandable fluid having a high coefficient of thermal expansion. The bellows has one end closed by a plate 119, which has a threaded stud 120 passing through the U-shaped member 112, and secured therein by a plurality of nuts 121.

The other end of the bellows is closed by the plate 118, which projects beyond the periphery of the bellows and is of sufficient size to engage the annular end 112 of the tubular hub 109. The variable diameter pulley 43 is shown at the position of maximum diameter which it assumes when the bellows 113 expands under influence of heat and forces the two sections closer together.

To do this the bellows reacts against the U-shaped member 112, which is carried by the pulley section 101, and its plate 118 engages the end 122 of the pulley section 102 and forces it toward the left in Fig. 5. When the bellows cools, it is adapted to permit the belt 44 to force the pulley sections 101, 102 apart, which permits the belt to ride farther down into the groove between the frusto-conical surfaces 105, 106, to decrease the effective diameter of the pulley 43.

The characteristics of the bellows and pulley sections and belt may be made such that the speed of rotation of the pulley 43, when driven by a constant speed motor 47 and an ordinary pulley, varies in proportion to the temperature of the expandible fluid in the bellows 113.

The speed of rotation increases as the temperature of the bellows 113 increases.

The present variable diameter pulley 43 may be controlled by the temperature of the air in the plenum chamber, by means of the arrangement shown in Figs. 5 and 6. In this embodiment the thermostat of the pulley 43 is surrounded by a housing 123, which is carried by the base 124, which has an enlarged aperture 125, surrounding the hub 109 (Fig. 5).

The housing may be made of insulating material, and it may support a porcelain cylinder or spool 126, about which there is wound helically a plurality of coils of resistance wire 127, the coils already being in the form of a small helix, in order to increase the length of the resistance wire.

The resistance coils 127 are adapted to be used

as heating coils, and are provided with a plurality of taps 128, 129, and 130, and the number of taps may be increased as desired, from three to four, five, six, or any number desired, for the purpose of increasing the steps or increments of resistance used in controlling the heat applied to the thermostat.

The number of taps shown is merely to be regarded as exemplary of one form of the invention.

The taps 128-130 from the resistance divide the resistance 127 into two sections 131 and 132, as shown in the wiring diagram of Fig. 6. The numbers applied to the taps have also been used for the conductors of this diagram, and M indicates the constant speed electric motor 47.

The bonnet 27 or boiler of the furnace is provided with a pressure responsive or thermally responsive switch 134, having a plurality of contacts adapted to be closed successively as temperature increases in the bonnet. For example, the switch 134 may include a bellows communicating with the thermal bulb 135 and actuating a movable switch arm 133, which is connected to the conductor 137.

The switch 134 has a plurality of fixed contacts, one of which is connected to the conductor 128, and the second one to the conductor 130.

The conductor 137, connected with the switch arm, leads to one side of the 110 volt electric light circuit 138. The variable diameter thermostatic pulley unit is shown at 43 in the diagram in position so that its thermostat is subjected to the heat from the heating element 127. The switch arm 133 is provided with an arcuate contact 141, which may connect one of the contacts or both of them.

The electric motor 47 has one of its terminals connected by conductor 139 to the power circuit 140, and the other terminal connected by a conductor 142 to a room thermostat 143, or to suitable relays in combination with the room thermostat. The other conductor 136 from the relays or room thermostat is connected to the other terminal 138 of the power line.

The operation of this circuit is as follows. It should be understood that the controlling switch 134 may be either a thermally responsive switch, subjected to the heat of the plenum chamber, or subjected to the heat of the water, or heat in the boiler, or it may be a pressure responsive switch, subjected to the pressure in the boiler. Normally the thermostat 113 of the variable diameter pulley 43 is cold, because the heaters 131, 132 are de-energized.

The pulley 43 has its sections 101, 102 far apart, and the diameter of the pulley 43 is at a minimum because the belt 44 is riding down closer to the shaft 34.

When the furnace is in operation, the energization of the motor 47 is controlled by the room thermostat and suitable relays 143, and a demand for heat in the room causes the energization of the motor 47, which drives the shaft 34 at a high speed because the pulley 43 has a small diameter.

Thus the motor 47 drives the screw 31 to supply coal, and the blower 33 to supply air, both at high speed.

As the temperature of the air in the plenum chamber increases, or as the temperature of the water in the boiler increases, or as the pressure of the steam or vapor in a steam or vapor system increases, the controlling element 134 is actuated to move the switch arm 133.

The first movement of the switch arm 133 connects the contact 141 with conductor 128 and energizes the heater 131. The heater 131 then heats the thermostat 113 and causes the pulley sections 101, 102 to approach each other, increasing the effective diameter of the pulley 43, and decreasing the speed of operation of the coal feeding screw 31 of the air blower 33.

As the temperatures or pressures mentioned above increase further, the arm 133 is moved further into contact with the fixed contact connected to conductor 130, also energizing the heater 132, which heats the thermostat 113 to a still higher temperature to press the pulley sections 101, 102 together to the position of Fig. 5.

This increases the effective diameter of the pulley 43 still further, and causes the screw 31 and the blower 33 to be driven at a still lower speed, decreasing the feeding of coal and the supply of air.

It should be understood that any number of additional heating element sections may be used with additional conductors and contacts on the controlling switch 134. Thus, the feed of the air and coal may be decreased as the furnace arrives at a higher temperature.

The operation of the complete system of Figs. 1 to 6 is as follows: The controlling circuit just described is adapted to regulate the cold air feed according to the furnace temperature, steam pressure, or water temperature. For any coal feed regulation from a high coal feed to a low feed, air for combustion must also be properly regulated.

The coal feed may be regulated by the speed changes which are brought about by the thermostatically controlled pulley driving the feed screw through the intermediary of the gears in the gear case 20. As the diameter of the pulley 43 is varied, the length of the belt 44 being constant, an increase in the diameter of the pulley 43 results in a pulling of the motor toward the left, or counterclockwise, in Fig. 1, against the tension of spring 56.

The belt 44, riding out farther toward the periphery of the pulley 43, pivots the motor 47 with its shaft 51. This causes the control crank 90 to move the connecting rod 92 toward the left in Fig. 2, which moves the air damper 39 toward the left to the position of Fig. 2, opening the air inlet 38 as the speed of operation of the shaft 34 decreases.

When the room thermostat calls for heat, starting the stoker, the furnace being cold, the stoker coal feed is operated at high speed and the air shutter is nearly closed. As the furnace temperature of a warm air furnace reaches 125 degrees F., for example, the heating element 131 is energized by the closing of electric contacts of the controlling element 134, and the thermostatically controlled pulley 43 changes its pitch diameter from small to large, thus reducing the speed of the shaft 34 and cutting down the speed of coal feed by the screw 41.

At the same time the blower speed is cut down, thus delivering less air, and in this instance the stoker would smoke unless some provision were made for supplying a sufficient amount of air.

In the present case, this is taken care of by the opening of the blower inlet 38 by means of the damper 39. This is brought about by the fact that as the thermostatically controlled pulley 43 expands it pulls the motor 47 toward the blower and moves the levers 90 and 96 (Fig. 3)

in a clockwise direction to open the damper 39.

This permits the blower to supply a proper amount of air to the combustion chamber because the blower inlet is opened farther as the speed of operation of the blower decreases, to counteract the tendency of the blower to diminish the air supply. Since the controlling element 134 is provided with a plurality of contacts, several stages of speed of operation may be provided, and in every case the air will be properly regulated, as the air shutter or damper 39 will be moved according to the coal feed and blower speed.

One of the most important advantages of this mode of operation is that the stoker is always stopped by the thermostat or furnace limit control when it is operating on low coal feed, with the blower inlet nearly wide open. This is advantageous because the blower inlet is then opened much farther than it is in the stokers of the prior art, and the natural draft of the flue is adapted to clear away all smoke and soot when the stoker is shut down. Then as the furnace cools naturally, the thermostat of the thermostatically controlled pulley cools also, as the electric current is cut off from the electric heating elements 132 and 134, successively.

The blower inlet is then slowly closed, which banks the fire automatically. This blower inlet is closed because, as the thermostatic element cools, it allows the belt tension spring 56 to force the pulley sections farther apart and move the motor 47 farther away from the blower. The movement of the motor then closes the air damper 39.

It should be noted that the air damper 39 does not effect a complete closure of the air inlet 38, but leaves the air inlet 38 sufficiently open to provide a supply of air for the next high fire start.

This is accomplished by having the damper 39 spaced from the opening 38. This control system is a marked advantage over the systems of the prior art because it is adapted to be used to estimate, in advance of the room thermostat or furnace limit switch, the heat demands of the house or furnace.

Referring to Fig. 8, this is a modification in which the shaft 34 is provided with an ordinary V pulley, and the shaft 46 is provided with a spring-pressed variable diameter pulley 100 of the type shown in Fig. 9.

The pulley 100 may be of the type shown in Fig. 9, in which this construction of the pulley is shown in detail. This pulley preferably includes a pair of relatively movable pulley sections 60 and 61, each of which is provided with one of the opposing frusto-conical surfaces 62, 63, which form the substantially V-shaped groove 64 for receiving the belt 44.

The pulley section 60 may be provided with an elongated hub 65 and may be fixedly mounted on the shaft 46 by means of a cylindrical bore 66 and a set screw 67. This hub 65 is provided with a suitable slot 68 and a key 69 for slidably engagement in a key-way 70 formed in the cylindrical bore 71 of the hub 72 of the pulley section 61.

Hub 72 is also elongated so that the two pulley sections have long complementary bearing surfaces 71 and 65 engaging each other and preventing any tilting of the sections relative to each other.

The frusto-conical belt-engaging surfaces 62, 63 are carried by the radially extending flanges 73 and 74. The hub 65 may be provided with a

reduced threaded portion 75 adapted to slidably receive a spring seat 76, which is secured in adjusted position by a nut and lock washer 77.

The spring seat 76 may consist of a metal member having a bore 78 for receiving the reduced portion 75 of the hub 65, and there may be a key 79 and a key-way 80 for preventing the relative rotation between the spring seat 76 and the member 75. The outer edge of the spring seat 76 has a cylindrical flange 81, which is adapted to retain the coil spring 82 in concentric relation with respect to the hub 65.

The other end of the coil spring 82 engages the radial flange 74 and surrounds a cylindrical portion 83. The spring 82 urges the two pulley sections 60 and 61 together, but the pulley sections are adapted to be forced apart by sufficient tension placed on the belt 44, which wedges its way between the surfaces 62, 63, when provided with sufficient tension, and forces the sections 60, 61 apart.

In this embodiment the motor is again pivotally mounted and urged in a counterclockwise direction by a motor tension spring 56, but the position of the motor is controlled by means of a thermostatically controlled bellows 150, one end of which is fixedly mounted on a bracket 151.

The other end of the bellows is connected by an adjustable length connecting rod 152 to a pivot pin 153 carried by a motor bracket 154. The bellows 150 is connected by a copper tube 155 to a thermally responsive bulb 156 or a source of boiler pressure and, as before described, the element 156 may be actuated responsive to bonnet temperature, water temperature, or boiler pressure, depending on whether the system is applied to a hot air furnace, a hot water boiler, or a steam or vapor system.

The operation of this system is similar to that previously described, except that no heating elements are required, since the bellows 150 may be directly connected to the controlling element 156, which is subjected to furnace temperature, water temperature, or boiler pressure.

The operation of this embodiment is similar to that previously described, except that the bellows 150 provides a uniform and constantly regulated coal and air feed from maximum speed at low furnace temperature, boiler temperature, or boiler pressure to slow rate of feed at high furnace temperature, furnace temperature, or boiler temperature.

The variation is brought about in this case by means of the thermostat 150, as follows: As the bellows 150 expands, the motor 47 rocks in a clockwise direction, and due to the belt 44 being of constant length, the belt is drawn farther into the groove of the variable diameter pulley 100, decreasing the effective diameter of the driving pulley, and decreasing the speed of operation of the coal feed and blower, with increase in temperature or pressure. The inlet to the blower is again opened as the coal feed is cut down, and the coal feeding is stopped. In this case the tilting of the motor causes the belt 44 to ride out farther in the groove 64 of the variable diameter pulley 100 as the temperature or pressure at the furnace increases. The operation is similar to that of Fig. 1.

Referring to Fig. 11, this is a modification in which the thermal bulb is not subjected to the temperature of the air in the furnace, but is responsive to the temperature of the bonnet of the furnace itself.

Referring to Fig. 7, this is a modification simi-

lar to Fig. 1, in that the shaft 34 is provided with a thermostatically controlled variable diameter pulley 43, but no electric heating elements are provided. Instead, the system is provided with an auxiliary blower 160, which may also have a thermostatically controlled variable diameter pulley 161, driven by a belt 162 from a pulley on the motor shaft 46, and the blower 160 is adapted to circulate the air through the plenum chamber 23.

The pulleys 161 and 43 may both be subjected to hot air from the plenum chamber 23 by means of a conduit 163 leading from the plenum chamber to an air chamber 164 surrounding the thermostat of the pulley 43 and an air chamber 165 surrounding the thermostat of the pulley 161.

In this case both the thermostats of the variable diameter pulleys 43 and 161 will be controlled by the temperature of the air in the plenum chamber, since air is conducted directly from the plenum chamber to these thermostats.

The speed of feed of the coal and the air of combustion will be decreased as the temperature of the air in the plenum chamber increases, and the speed of circulation of the air through the plenum chamber will be increased as the temperature of the air in the plenum chamber increases.

The present invention is adapted to decrease the consumption of coal and to effect better combustion in stoker operated furnaces or boilers. There is never a deep coal bed left in the furnace, and the coal bed may vary from approximately three inches, when there is a low bed, to six inches deep during the high firing period.

After the coal bed has reached a thickness of, for example, six inches on the high firing period, the stoker is cut to low feed at a temperature of, for example, 125 degrees F. of the warm air in the plenum chamber, or, for example, at two pounds or five pounds steam.

Then the coal, which has been brought in at high feed, is burned up, and the thickness of the fire bed is reduced before the limit switch setting is reached. On a warm air gravity circulation installation, the limit switch is usually set at about 300 or 350 degrees F.; on a five pound steam installation, the stoker is cut to low feed in approximately two pounds steam pressure; and on a hot water installation, with a maximum limit switch setting of 180 degrees F., the stoker is cut to low feed at 125 to 140 degrees F., depending on the load on the boiler.

The result is that it is practically impossible to bring the furnace or boiler temperature up to the limit switch setting because, as the coal feed and air feed is reduced, the excess coal, which is forced into the furnace while on high feed, is consumed before the limit temperatures are reached. In other words, the small amount of coal fed on low fire, plus the surplus fed on high, will be consumed, and the fire bed is reduced to a point where it will carry the heating load on low fire and when shut down there is left only a shallow fuel bed. Therefore, there is no overrun, and practically no smoke or soot, with an installation made according to the present invention.

The present invention results in the regulation of the coal and air feed according to the demands on the furnace. This invention also eliminates the tendency of some of the devices of the prior art to form clinkers, which melt into a slag and run down into the retort, closing the air ports, and burning on the end of the worm.

The present invention also has the advantage that fresh or green coal is coming up through the retort at low feed, to force the heated coals away, and up to the top of the fire bed; and there is always sufficient fuel to maintain the pilot or kindling fire, in the retort.

According to the present invention, the coal feed is at all times feeding some coal on low setting, which eliminates the bad operating results that are inherent in the devices of the prior art.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a stoker controlling system, the combination of a driving motor with a coal feeding means adapted to be driven by said motor, a blower for supplying air for combustion, pulley means for driving said blower and coal feeding means, pulley means driven by said motor at substantially constant speed, one of said pulley means comprising a variable diameter V pulley interposed between the motor and the coal feed and blower, and thermostatic means for directly controlling the effective diameter of said pulley, whereby the rate of feed of coal may be controlled substantially proportionally to the temperature of said thermostatic means.

2. In a fuel supply system for stokers, the combination of a retort with a coal feeding member for feeding coal to said retort, an air supply conduit for providing a supply of air for combustion, a driving motor for driving said blower and said coal feeding member, said motor being movably mounted upon a support, a pair of V pulleys carried by the shafts of said blower and motor, one of said V pulleys being a variable diameter pulley having a pair of movable sections provided with frusto-conical surfaces for engaging the edges of a wedge-shaped belt, and thermostatic means for controlling the effective diameter of said variable diameter pulley whereby the speed of drive of said blower and fuel feeding member may be varied responsive to temperature conditions while driven with a constant speed motor.

3. In a fuel supply system for stokers, the combination of a retort with a coal feeding member for feeding coal to said retort, an air supply conduit for providing a supply of air for combustion, a driving motor for driving said blower and said coal feeding member, said motor being movably mounted upon a support, a pair of V pulleys carried by the shafts of said blower and motor respectively, one of said V pulleys being a variable diameter pulley having a pair of movable sections provided with frusto-conical surfaces for engaging the edges of a wedge-shaped belt, and thermostatic means for controlling the effective diameter of said variable diameter pulley whereby the speed of drive of said blower and fuel feeding member may be varied responsive to temperature conditions while driven with a constant speed motor, said thermostatic means being carried by the same shaft which supports said variable diameter pulley and acting on one section to move it relative to the other.

4. In a fuel supply system for stokers, the combination of a retort with a coal feeding member

for feeding coal to said retort, a blower and an air supply conduit for providing a supply of air for combustion, a driving motor for driving said blower and said coal feeding member, said motor being movably mounted upon a support, a pair of V pulleys carried by the shafts of said blower and motor, one of said V pulleys being a variable diameter pulley having a pair of movable sections provided with frusto-conical surfaces for engaging the edges of a wedge-shaped belt, and thermostatic means for controlling the effective diameter of said variable diameter pulley and the position of said motor, whereby the speed of drive of said blower and fuel feeding member may be varied responsive to temperature conditions while driven with a constant speed motor, valve means adapted to control the flow of air in said air conduit and operative connecting means between said valve means and said motor whereby the movement of the motor acts to control the opening or closing of said valve means tending to provide an increased supply of air when the pressure of said blower is diminished by reason of a lower speed.

5. In a fuel supply for stokers, the combination of a retort with a coal feeding member for feeding coal to said retort, a blower for providing a supply of air for combustion to said retort, a driving motor for driving said blower and said coal feeding member, said blower and coal feeding member having a common driving shaft, a V pulley mounted on said common driving shaft, a V pulley mounted on the motor shaft and a wedge-shaped belt connecting said V pulleys, one of said V pulleys being a variable diameter pulley having a pair of movable sections provided with frusto-conical surfaces for engaging the edges of a wedge-shaped belt, valve means for controlling the flow of the air of combustion supplied by said blower, and regulating means controlled responsive to the condition of heat generation of the heater and arranged and constructed to decrease the speed of operation of said common drive shaft by changing the distance between said frusto-conical surfaces and to move said valve means whereby the flow of combustion air to the retort is decreased and the rate of feed of coal to the retort is decreased as the heater reaches a predetermined condition with respect to the generation and storage of heat energy at the heater.

6. In a fuel supply for stokers, the combination of a retort with a coal feeding member for feeding coal to said retort, a blower for providing a supply of air for combustion to said retort, a driving motor for driving said blower and said coal feeding member, said blower and coal feeding member having a common driving shaft, a V pulley mounted on said common driving shaft, a V pulley mounted on the motor shaft and a wedge-shaped belt connecting said V pulleys, one of said V pulleys being a variable diameter pulley having a pair of movable sections provided with frusto-conical surfaces for engaging the edges of a wedge-shaped belt, valve means for controlling the flow of the air of combustion supplied by said blower, and regulating means controlled responsive to the condition of heat generation of the heater and arranged and constructed to decrease the speed of operation of said common drive shaft by changing the distance between said frusto-conical surfaces and to move said valve means whereby the flow of combustion air to the retort is decreased and the rate of feed of coal to the retort is decreased as the heater reaches a predetermined condition with respect to the generation and storage of heat energy at the heater, said regulating means comprising a pres-

sure responsive switch having a plurality of contacts for controlling an electric heater, and a thermostat for controlling the relative positions of the parts of the variable diameter V pulley, said thermostat being controlled by said heater.

7. In a fuel supply for stokers, the combination of a retort with a coal feeding member for feeding coal to said retort, a blower for providing a supply of air for combustion to said retort, a driving motor for driving said blower and said coal feeding member, said blower and coal feeding member having a common driving shaft, a V pulley mounted on said common driving shaft, a V pulley mounted on the motor shaft and a wedge-shaped belt connecting said V pulleys, one of said V pulleys being a variable diameter pulley having a pair of movable sections provided with frusto-conical surfaces for engaging the edges of a wedge-shaped belt, valve means for controlling the flow of the air of combustion supplied by said blower, and regulating means controlled responsive to the condition of heat generation of the heater and arranged and constructed to decrease the speed of operation of said common drive shaft by changing the distance between said frusto-conical surfaces and to move said valve means whereby the flow of combustion air to the retort is decreased and the rate of feed of coal to the retort is decreased as the heater reaches a predetermined condition with respect to the generation and storage of heat energy at the heater, said regulating means comprising a thermostatic switch subjected to heat from the heater and controlling an electric heater, and a thermostat heated by said electric heater for controlling the relative positions of the parts of the variable diameter pulley.

8. In a fuel supply system for stokers, the combination of a retort with a coal feeding member for feeding coal to said retort, a blower and an air supply conduit for providing a supply of air for combustion, a driving motor for driving said blower and said coal feeding member, said motor being movably mounted upon a support, a pair of V pulleys carried by the shafts of said blower and motor, one of said V pulleys being a variable diameter pulley having a pair of movable sections provided with frusto-conical surfaces for engaging the edges of a wedge-shaped belt, and thermostatic means for controlling the effective diameter of said variable diameter pulley and the position of said motor whereby the speed of drive of said blower and fuel feeding member may be varied responsive to temperature conditions while driven with a constant speed motor, valve means adapted to control the flow of air in said air conduit and operative connecting means between said valve means and said motor whereby the movement of the motor acts to control the opening or closing of said valve means to provide an increased supply of air when the pressure of said blower is diminished by reason of a lower speed, said thermostatic means comprising a thermostat adapted to act on one pulley section and react on the other pulley section to effect a relative movement between the movable sections of the variable diameter pulley.

9. In a fuel supply system for stokers, the combination of a retort with a coal feeding member for feeding coal to said retort, a blower and an air supply conduit for providing a supply of air for combustion, a driving motor for driving said blower and said coal feeding member, said motor being movably mounted upon a support, a pair

of V pulleys carried by the shafts of said blower and motor, one of said V pulleys being a variable diameter pulley having a pair of movable sections provided with frusto-conical surfaces for engaging the edges of a wedge-shaped belt, and thermostatic means for controlling the effective diameter of said variable diameter pulley and the position of said motor whereby the speed of drive of said blower and fuel feeding member may be varied responsive to temperature conditions while driven with a constant speed motor, valve means adapted to control the flow of air in said air conduit and operative connecting means between said valve means and said motor whereby the movement of the motor acts to control the opening or closing of said valve means to provide an increased supply of air when the pressure of said blower is diminished by reason of a lower speed, said thermostatic means comprising a thermostat adapted to act on one pulley section and react on the other pulley section to effect a relative movement between the movable sections of the variable diameter pulley, said thermostatic means being enclosed in a housing, and an electric heater enclosed in said housing for heating said thermostatic means responsive to the energization of said electric heater.

10. In a fuel supply system for stokers, the combination of a retort with a coal feeding member for feeding coal to said retort, a blower and an air supply conduit for providing a supply of air for combustion, a driving motor for driving said blower and said coal feeding member, said motor being movably mounted upon a support, a pair of V pulleys carried by the shafts of said blower and motor, one of said V pulleys being a variable diameter pulley having a pair of movable sections provided with frusto-conical surfaces for engaging the edges of a wedge-shaped belt, and thermostatic means for controlling the effective diameter of said variable diameter pulley and the position of said motor whereby the speed of drive of said blower and fuel feeding member may be varied responsive to temperature conditions while driven with a constant speed motor, valve means adapted to control the flow of air in said air conduit and operative connecting means between said valve means and said motor whereby the movement of the motor acts to control the opening or closing of said valve means to provide an increased supply of air when the pressure of said blower is diminished by reason of a lower speed, said thermostatic means comprising a thermostat adapted to act on one pulley section and react on the other pulley section to effect a relative movement between the movable sections of the variable diameter pulley, said thermostatic means being enclosed in a housing, and an electric heater enclosed in said housing for heating said thermostatic means responsive to the energization of said electric heater, and a second thermostatic means located to be actuated responsive to temperature conditions at the heater for controlling the energization of said first-mentioned thermostatic means.

11. In a fuel supply system for stokers, the combination of a retort with a coal feeding member for feeding coal to said retort, a blower and an air supply conduit for providing a supply of air for combustion, a driving motor for driving said blower and said coal feeding member, said motor being movably mounted upon a support, a pair of V pulleys carried by the shafts of said blower and motor, one of said V pulleys being a variable diameter pulley having a pair of mov-

able sections provided with frusto-conical surfaces for engaging the edges of a wedge-shaped belt, and thermostatic means for controlling the effective diameter of said variable diameter pulley and the position of said motor whereby the speed of drive of said blower and fuel feeding member may be varied responsive to temperature conditions while driven with a constant speed motor, valve means adapted to control the flow of air in said air conduit and operative connecting means between said valve means and said motor whereby the movement of the motor acts to control the opening or closing of said valve means to provide an increased supply of air when the pressure of said blower is diminished by reason of a lower speed, said thermostatic means comprising a thermostat adapted to act on one pulley section and react on the other pulley section to effect a relative movement between the movable sections of the variable diameter pulley, said thermostatic means being enclosed in a housing, and an electric heater enclosed in said housing for heating said thermostatic means responsive to the energization of said electric heater, and switch means controlled by a pressure responsive device responsive to the pressure of a boiler for controlling the energization of said heater.

12. In a fuel supply system for stokers, the combination of a retort with a coal feeding member for feeding coal to said retort, a blower and an air supply conduit for providing a supply of air for combustion, a driving motor for driving said blower and said coal feeding member, said motor being movably mounted upon a support, a pair of V pulleys carried by the shafts of said blower and motor, one of said V pulleys being a variable diameter pulley having a pair of movable sections provided with frusto-conical surfaces for engaging the edges of a wedge-shaped belt, and thermostatic means for controlling the effective diameter of said variable diameter pulley and the position of said motor whereby the speed of drive of said blower and fuel feeding member may be varied responsive to temperature conditions while driven with a constant speed motor, valve means adapted to control the flow of air in said air conduit and operative connecting means between said valve means and said motor whereby the movement of the motor acts to control the opening or closing of said valve means to provide an increased supply of air when the pressure of said blower is diminished by reason of a lower speed, and a controlling device controlled responsive to the generation of a predetermined amount of heat energy at the heater containing said retort for controlling the action of said thermostatic means whereby the combustion is cut down as the heated condition of the heater increases to reduce the amount of over-run of temperature.

13. In a fuel supply for stokers, the combination of a retort with a coal feeding member for feeding coal to said retort, a blower for providing a supply of air for combustion to said retort, a driving motor for driving said blower and said coal feeding member, said blower and coal feeding member having a common driving shaft, a V pulley mounted on said common driving shaft, a V pulley mounted on the motor shaft and a wedge-shaped belt connecting said V pulleys, one of said V pulleys being a variable diameter pulley having a pair of movable sections provided with frusto-conical surfaces for engaging the edges of a wedge-shaped belt, and regulating means controlled responsive to the condition of heat generation of the heater and arranged and

constructed to decrease the speed of operation of said common drive shaft by changing the distance between said frusto-conical surfaces, whereby the rate of feed of coal to the retort is decreased as the heater reaches a predetermined condition with respect to the generation and storage of heat energy at the heater.

14. In a fuel supply for stokers, the combination of a retort with a coal feeding member for feeding coal to said retort, a blower for providing a supply of air for combustion to said retort, a driving motor for driving said blower and said coal feeding member, said blower and coal feeding member having a common driving shaft, a V pulley mounted on said common driving shaft, a V pulley mounted on the motor shaft and a wedge-shaped belt connecting said V pulleys, one of said V pulleys being a variable diameter pulley having a pair of movable sections provided with frusto-conical surfaces for engaging the edges of a wedge-shaped belt, and regulating means controlled responsive to the condition of heat generation of the heater and arranged and constructed to decrease the speed of operation of said common drive shaft by changing the distance between said frusto-conical surfaces, whereby the rate of feed of coal to the retort is decreased as the heater reaches a predetermined condition with respect to the generation and storage of heat energy at the heater, said regulating means comprising a pressure responsive switch having a plurality of contacts for controlling an electric heater, and a thermostat for controlling the relative positions of the parts of the variable diameter V pulley, said thermostat being controlled by said heater.

15. In a fuel supply for stokers, the combination of a retort with a coal feeding member for feeding coal to said retort, a blower for providing a supply of air for combustion to said retort, a driving motor for driving said blower and said coal feeding member, said blower and coal feeding member having a common driving shaft, a V pulley mounted on said common driving shaft, a V pulley mounted on the motor shaft and a wedge-shaped belt connecting said V pulleys, one of said V pulleys being a variable diameter pulley having a pair of movable sections provided with frusto-conical surfaces for engaging the edges of a wedge-shaped belt, and regulating means controlled responsive to the condition of heat generation of the heater and arranged and constructed to decrease the speed of operation of said common drive shaft by changing the distance between said frusto-conical surfaces whereby the rate of feed of coal to the retort is decreased as the heater reaches a predetermined condition with respect to the generation and storage of heat energy at the heater, said regulating means comprising a thermostatic switch subjected to heat from the heater and controlling an electric heater, and a thermostat heated by said electric heater for controlling the relative positions of the parts of the variable diameter pulley.

16. In a fuel supply system for stokers, the combination of a retort with a coal feeding member for feeding coal to said retort, a blower and an air supply conduit for providing a supply of air for combustion, a driving motor for driving said blower and said coal feeding member, said motor being movably mounted upon a support, a pair of V pulleys carried by the shafts of said blower and motor, one of said V pulleys being a variable diameter pulley having a pair of movable sections provided with frusto-conical sur-

faces for engaging the edges of a wedge-shaped belt, and thermostatic means for controlling the effective diameter of said variable diameter pulley and the position of said motor whereby the speed of drive of said blower and fuel feeding member may be varied responsive to temperature conditions while driven with a constant speed motor, said thermostatic means comprising a thermostat adapted to act on one pulley section and react on the other pulley section to effect a relative movement between the movable sections of the variable diameter pulley.

17. In a fuel supply system for stokers, the combination of a retort with a coal feeding member for feeding coal to said retort, a blower and an air supply conduit for providing a supply of air for combustion, a driving motor for driving said blower and said coal feeding member, said motor being movably mounted upon a support, a pair of V pulleys carried by the shafts of said blower and motor, one of said V pulleys being a variable diameter pulley having a pair of movable sections provided with frusto-conical surfaces for engaging the edges of a wedge-shaped belt, and thermostatic means for controlling the effective diameter of said variable diameter pulley and the position of said motor whereby the speed of drive of said blower and fuel feeding member may be varied responsive to temperature conditions while driven with a constant speed motor, said thermostatic means comprising a thermostat adapted to act on one pulley section and react on the other pulley section to effect a relative movement between the movable sections of the variable diameter pulley, and an electric heater for heating said thermostatic means responsive to the energization of said electric heater.

18. In a fuel supply system for stokers, the combination of a retort with a coal feeding member for feeding coal to said retort, a blower and an air supply conduit for providing a supply of air for combustion, a driving motor for driving said blower and said coal feeding member, said motor being movably mounted upon a support, a pair of V pulleys carried by the shafts of said blower and motor, one of said V pulleys being a variable diameter pulley having a pair of movable sections provided with frusto-conical surfaces for engaging the edges of a wedge-shaped belt, and thermostatic means for controlling the effective diameter of said variable diameter pulley and the position of said motor whereby the speed of drive of said blower and fuel feeding member may be varied responsive to temperature conditions while driven with a constant speed motor, said thermostatic means comprising a thermostat adapted to act on one pulley section and react on the other pulley section to effect a relative movement between the movable sections of the variable diameter pulley, and an electric heater for heating said thermostatic means responsive to the energization of said electric heater, and a second thermostatic means located to be actuated responsive to temperature conditions at the heater for controlling the energization of said first-mentioned thermostatic means.

19. In a fuel supply system for stokers, the combination of a retort with a coal feeding member for feeding coal to said retort, a blower and an air supply conduit for providing a supply of air for combustion, a driving motor for driving said blower and said coal feeding member, said motor being movably mounted upon a support, a pair of V pulleys carried by the shafts of said blower and motor, one of said V pulleys being a

variable diameter pulley having a pair of movable sections provided with frusto-conical surfaces for engaging the edges of a wedge-shaped belt, and thermostatic means for controlling the effective diameter of said variable diameter pulley and the position of said motor whereby the speed of drive of said blower and fuel feeding member may be varied responsive to temperature conditions while driven with a constant speed motor, said thermostatic means comprising a thermostat adapted to act on one pulley section and react on the other pulley section to effect a relative movement between the movable sections of the variable diameter pulley, and an electric heater for heating said thermostatic means responsive to the energization of said electric heater, and switch means controlled by a pressure responsive device responsive to the pressure of a boiler for controlling the energization of said heater.

20. In a fuel supply system for stokers, the combination of a retort with a coal feeding member for feeding coal to said retort, a blower and an air supply conduit for providing a supply of air

for combustion, a driving motor for driving said blower and said coal feeding member, said motor being movably mounted upon a support, a pair of V pulleys carried by the shafts of said blower and motor, one of said V pulleys being a variable diameter pulley having a pair of movable sections provided with frusto-conical surfaces for engaging the edges of a wedge-shaped belt, and thermostatic means for controlling the effective diameter of said variable diameter pulley and the position of said motor whereby the speed of drive of said blower and fuel feeding member may be varied responsive to temperature conditions while driven with a constant speed motor, and a controlling device controlled responsive to the generation of a predetermined amount of heat energy at the heater containing said retort for controlling the action of said thermostatic means whereby the combustion is cut down as the heated condition of the heater increases to reduce the amount of over-run of temperature.

WILLIAM W. HALLINAN.
